UNITED STATES PATENT OFFICE.

PETER A. POPPE, OF COVENTRY, ENGLAND.

CARBURETER FOR INTERNAL-COMBUSTION ENGINES.

1,007,729.

Specification of Letters Patent. Patented Nov. 7, 1911.

Application filed February 6, 1909. Serial No. 476,402.

To all whom it may concern:

Be it known that I, PETER AUGUST POPPE, a subject of the King of Great Britain, residing at Drake street, Lockhurst Lane, Cov- 5 entry, Warwickshire, England, have invented certain Improvements in or Relating to Carbureters for Internal-Combustion Engines, of which the following is a specifica-
tion.

10 This invention relates to carbureters for internal combustion engines, of that type in which the jet outlet is opened up simultaneously with the air supply and throttle. Carbureters of this type are usually so constructed and adjusted that the ratio of petrol to air supplied at all positions of the operating lever gives maximum efficiency combined with good fuel economy. It is found however that in certain cases insufficient petrol 20 is supplied during acceleration, especially if rapid acceleration is required. If an adjustment to supply slightly more petrol is made maximum economy is not obtained.

The object of this invention is to enable 25 both good economy with efficiency and also quick acceleration to be obtained without employing a separate control device.

The accompanying drawings show the application of the invention to a carbureter of 30 the type described in my prior Patent No. 883,740.

In these, Figure 1 is a central vertical section of a spray carbureter, and Fig. 2 is a transverse section on the line 2-2 of Fig. 1. 35 Like letters indicate like parts in both drawings, and where possible the lettering is the same as in the drawings of the prior patent.

Thus the jet nozzle is lettered A, and at- 40 tached to it is a conically closed end A¹ provided with an eccentrically located hole A².

In the carbureter chamber E is located the throttle valve F which is provided with two ports or openings F¹, F². These ports are 45 adapted to register with the carbureted air outlet H and the air inlet H², as shown. The valve F is formed with a flange X which has in it a short slot Y. This is engaged by a pin L formed on a flange K¹ integral with 50 the cap K mounted on and similar in shape to the jet nozzle A, A¹. This cap K is formed with an eccentric outlet hole K² adapted to coincide with the hole A² and be moved out of register therewith. Attached 55 to the cap K is a stem Z carrying a control lever J. A light spring M is used to hold

the parts down and keep the cap K in contact with the jet.

To operate the carbureter the lever J is rotated, rotating the cap K over the jet nozzle, cutting down the outlet from the jet by causing the holes K² and A² to move out of register. By the connection L, Y the throttling valve F is rotated bringing the ports F¹, F² out of register with the passages H, 60 H². Thus as the control lever is moved in one direction the fresh air inlet, fuel outlet, and carbureted air outlet are all simultaneously cut down or opened up, as described in the prior patent specification. 65

It will be noticed that the jet cap K is directly connected with the control lever J and that the throttle valve is rotated through the pin and slot L and Y. Thus when the lever J is moved the pin moves in the slot 70 so that the jet is actuated without the throttle valve being moved until the pin has reached the end of the slot. The throttle valve is then picked up and rotated with the jet cap. Thus for first movement of the lever in one direction the jet is controlled, and subsequently the various valves simultaneously. 75

In carbureters of the type in which the jet outlet is controlled with the throttle 80 valve or air inlet, or both, it is found that rapid acceleration is not obtainable except by the sacrifice of economy. That is to say that if the jet outlet is of certain size to provide economy, it is not big enough for 85 purposes of quick acceleration. The construction illustrated obviates this, as during acceleration the lever J is moved to open the throttle valve, but it has the effect of first opening up the jet outlet above its normal. 90 The throttle and air valves are then moved to progressively open up the carbureter. Thus a relatively rich mixture is provided while the carbureter is being opened up. After having reached the desired speed, to 95 obtain the economy required the operating lever J is moved back slightly. This has the effect of moving the pin to the other end of the slot, slightly closing up the jet outlet but not affecting the position of the 100 throttle or air valves. Further movement of the operating lever J moves all three valves simultaneously owing to the pin L being at the end of the slot Y. Thus during slowing down the carbureter is set economically. If at any speed it is required to 105 slightly enrich or slightly weaken the mix- 110

ture this can be done by moving the control lever slightly in the required direction which moves the jet cap K to enlarge or decrease the outlet without affecting the position of the 5 throttle and air valves. It will be seen that in this manner both good economy during normal running can be obtained, and likewise a richer mixture under certain conditions, providing good acceleration and hill 10 climbing power. It will be noticed that this improved acceleration is obtained throughout the whole range, that is to say, the richer mixture is obtainable throughout the whole 15 range of opening of the carburetor and the choice of slight variation of the mixture is offered at any position of the throttle valve.

What I claim as my invention, and desire to secure by Letters Patent is:—

In a carburetor, the combination with a 20 casing having an air inlet and a carbureted air outlet, of a cylindrical throttle valve rotatably mounted within the casing and having ports adapted to simultaneously control the said air inlet and carbureted air outlet,

said throttle valve also having an inwardly-extending flange, a cap projecting upwardly above said flange and arranged concentrically within the throttle valve and having an outwardly-extending flange and also an eccentric outlet opening, a jet nozzle arranged within the cap and having an opening with which the opening in the cap is adapted to be brought into and out of register when the cap is turned, means for turning the cap, and a pin and slot connection 30 between the flanges on the cap and throttle valve whereby to permit the cap to at first turn slightly in relation to the throttle to cause the jet outlet to be operated and to thereafter cause the cap and throttle valve 35 to move together.

In testimony whereof I have signed my name to this specification in the presence of two subscribing witnesses.

P. A. POPPE.
